UNITED STATES PATENT OFFICE.

THOMAS G. PENN, OF CHICAGO, ILLINOIS.

CALENDAR.

Application filed September 1, 1923. Serial No. 680,560.

To all whom it may concern:

Be it known that I, THOMAS G. PENN, a citizen of the United States, residing at Chicago, in the county of Cook and State of Illinois, have invented new and useful Improvements in Calendars, of which the following is a specification.

This invention relates to calendars and more particularly to a calendar designed for 10 mounting upon lead pencils, an object of the invention being to provide a practical, novel construction of calendar device which may be easily operated so as to enable the user to readily determine the date of the month, 15 week and year.

Another object of this invention is to provide a calendar structure as specified which embodies a plurality of independently adjustable members to permit adjustment for 20 showing dates and days.

Other objects of the invention will appear in the following detailed description taken in connection with the accompanying drawing wherein:

25 Fig. 1 is a side elevation of the improved calendar structure showing it applied.

Fig. 2 is a side elevation of the calendar structure showing a different part from that illustrated in Fig. 1.

30 Fig. 3 is a side elevation showing the number carrying member of the calendar structure.

Fig. 4 is a cross section on the line 4—4 of Fig. 1.

35 Fig. 5 is a longitudinal section through the calendar structure.

Fig. 6 is a fragmentary longitudinal section through the calendar taken at a different point from the section shown in 40 Fig. 5.

Fig. 7 is a side elevation of one of the plates embodied in the calendar structure.

Fig. 8 is a side elevation of the month carrying plate of the calendar structure.

45 Referring more particularly to the drawings, the improved calendar structure is adapted for mounting upon a pencil 1 or analogous structure and it comprises a sheet 2 of paper which has the numbers 1 to 0 printed thereon as shown at 3. A relatively thin metal sleeve 4 is mounted over the number carrying paper 2 and is provided with openings 5 to permit the exhibiting of the numbers. The plate 4 serves as a protector 50 for the paper to prevent mutilation thereof in the adjustment of the other parts of the

calendar structure to be hereinafter more specifically described.

A sleeve 6 is rotatably mounted about the sleeve 4 and in spaced relation thereto 60 so as to permit various slides 7, 8 and 9 to be positioned between the sleeves 4 and 6. The slide 7 has the days of the week printed thereon as shown at 10 while the slide 8 has the months of the year printed thereon as shown at 11. Each of the slides 7 and 8 has an ear 12 formed thereon which extends through a slot 13 in the sleeve 6 and through a slot 14 in an outer sleeve 15. The sleeves 6 and 15 are provided with transversely extending slots 17 and 18 through which the names of the days of the week and of the months of the year are visible, respectively as indicated in Fig. 1 of the drawings. By sliding the plates 7 and 8, through the 70 medium of the ears 12 the calendar may be adjusted to properly show the day of the week and the month of the year.

The slide 9 has the numbers 1 and 2 printed thereon as shown at 19 in Fig. 1 80 of the drawings and it is slidable behind an opening 20 in the sleeve 15. The sleeves 6 and 15 are provided with aligning openings 22 which are adapted to align with anyone of the openings 5 to permit the exhibition of anyone of the numbers 3 on the paper 2 for indicating the day of the month. During the first nine days of the month, both the numbers 1 and 2 on the slide 9 are hidden by the outer sleeve 15, however, when 90 the tenth of the month is reached the number 1 on the slide 9 is moved into exhibiting position through the opening 20 and is maintained in this position until the twentieth of the month is reached when the 95 number 2 is moved into exhibiting position. The X printed on the paper as indicated at 3' is made to simulate 30 or 31 whichever happens to be the last day of the month.

The sleeve 15 is provided with an opening 26 through which the year is exhibited such as 1923, as shown in Fig. 1 of the drawings. The sleeves 15 and 6 are rotatable and slidable relative to the inner sleeve 4, so as to permit partial rotation to bring the 100 numbers 3 in the different rows, into exhibiting position relative to the opening 21. From this it will be apparent that after the tenth of the month has been reached in operating the device, the proper numerals for 110 indicating the days may be brought into registering position before the openings 20

and 21. The plates 7, 8 and 9 rotate with the sleeves 6 and 15 owing to the connection of the sleeves and plates through the medium of the ears 12. The plate 9 has a transversely extending ear 27 formed thereon to facilitate its adjustment.

It is, of course, to be understood that the invention may be constructed in other manners and the parts associated in different relations and, therefore, I do not desire to be limited in any manner except as set forth in the claims hereunto appended.

Having thus described my invention what I claim is:

15. 1. A calendar attachment for pencils comprising, a pencil carried number bearing member, a protecting sleeve mounted over said member, an outer sleeve rotatable relative to said protecting sleeve and provided with an opening to permit exhibition of the numbers on said member therethrough, said outer sleeve having an additional opening in alignment with the first opening, a plate mounted for sliding movement relative to the outer sleeve having numbers thereon to be exhibited thru the additional opening at predetermined times, day and month indicating plates slidably supported inwardly of said outer sleeve, said outer sleeve provided with longitudinally extending slots, ears formed on said last mentioned slideable plates and protruding through said slots for connecting the plates for rotary movement with the outer sleeve and to permit adjustment of the plates longitudinally relative to the outer sleeve.
20. 25. the outer sleeve having numbers thereon to be exhibited thru the additional opening at predetermined times, day and month indicating plates slidably supported inwardly of said outer sleeve and said outer sleeve

having openings to permit the exhibiting of the names of the days and months therethrough.

2. A calendar attachment for pencils comprising, a pencil carried number bearing member, a protecting sleeve mounted over said member, an outer sleeve rotatable relative to said protecting sleeve and provided with an opening to permit exhibition of the numbers on said member therethrough, an additional opening in alignment with the first opening, a plate mounted for sliding movement relative to the outer sleeve having numbers thereon to be exhibited thru the additional opening at predetermined times, day and month indicating plates slidably supported inwardly of said outer sleeve, said outer sleeve provided with openings to permit the exhibiting of the names of the days and months therethrough, said outer sleeve provided with longitudinally extending slots, ears formed on said last mentioned slideable plates and protruding through said slots for connecting the plates for rotary movement with the outer sleeve and to permit adjustment of the plates longitudinally relative to the outer sleeve.

In testimony whereof I affix my signature.
THOMAS G. PENN.
